UNITED STATES PATENT OFFICE.

ROBERT C. ANDERSON AND FREDERICK F. RIKE, OF DAYTON, OHIO, ASSIGNEES TO
BUCKEYE IRON & BRASS WORKS, OF DAYTON, OHIO, A CORPORATION OF OHIO.

EXHAUST WHISTLE.

Application filed February 3, 1923. Serial No. 616,818.

To all whom it may concern:

Be it known that we, ROBERT C. ANDERSON and FREDERICK F. RIKE, citizens of the United States, residing at Dayton, in the 5 county of Montgomery and State of Ohio, have invented certain new and useful Improvements in Exhaust Whistles, of which the following is a specification, reference being had therein to the accompanying drawing.

Our invention relates to signals, and in particular to signals attached to the exhaust pipes of automotive engines, which are operated by the pressure of the gases exhausting therefrom.

It is the object of our invention to provide a whistle which can be operated by the exhaust from automotive engines and attached to the exhaust pipe thereof.

It is the further object of our invention to provide a whistle which may be composed of two simple parts readily detachable from one another without removing the entire whistle from the exhaust pipe so that 25 the whistle may be cleaned of the accumulations of carbon and the like which accumulate in such structures due to deposits from the exhaust gases.

It is the further object of our invention 30 to provide a simple and rugged construction for controlling the exhaust of gases through the exhaust pipe and controlling them in their relation to the whistle.

It is the further object of our invention 35 to provide means of combining in one structure two exhaust lines and utilizing the single control valve for diverting the exhaust gases to the whistle of the character described.

Referring to the drawings;

Figure 1 is a section through the dual exhaust line, a single exit line, a valve and a whistle.

Figure 2 is a view partially in section 45 showing the valve and the yielding means for returning it to its position of rest.

Figure 3 is a plan view of Figure 4.

Figure 4 is a section through the lower half of the whistle.

Figure 5 is a section through the upper half of the whistle.

Figure 6 is a section on the line 6—6 of Figure 5.

Referring to the drawings in detail, 55 1 is a tubular casing in which there is located

transversely thereto, a valve shaft 2 on which is mounted a valve consisting of the wings 3 and 4 which are joined together by a hub 5 mounted on the shaft 2. This shaft has mounted on one end thereof, surrounding it, a helical spring 6. One end of the helical spring is attached at 7 to the shaft 2 and the other end is attached as at 8 to the casing 1, so that the valve is always held 60 yieldingly in a given position from which it is moved by the arm 9 which is mounted on the shaft 2. This arm is connected by any suitable means such as a cable to a handle adjacent the driver's seat, or may be operated from the rear step by the same 65 method.

This casing 1 carries a boss 10 having threads 11 on the interior thereof, in which there is screwed the lower half of the whistle. This lower half consists of a body 75 12 on which are formed threads 13 for engaging with the threads 11. This portion of the whistle has a passageway 14 therethrough which is enlarged into a chamber 15 surrounded by a wall 16 on which there are 80 provided a plurality of flat faces 17 for engaging with a wrench, to facilitate the rotation of the whistle when it is being screwed into the casing 1 or detached therefrom. The upper end of the wall 16 is enlarged 85 and exteriorly threaded as shown, and screwed thereonto is a collar-like internally threaded lower end 19 of a dome 26 which forms the upper half of the whistle. Grub screws 20 are provided for preventing casual 90 detachment of the upper and lower halves from one another.

The wall 16 of the lower half has rising therefrom a plurality of integral standards 22 arranged at spaced intervals and formed 95 integral with a cap or disk 21 at their upper ends. Both the cap member and the standards are located a predetermined distance back from the outer edge of 16 so that when the collar 19 of the upper half of the whistle 100 is threaded thereon it is spaced from the cap member and its standards a distance sufficient for allowing the exhaust gases to pass through 14 and 15 between the standards as at 23 and through the space between 19 and 21 as at 24.

A series of spaced arch-shaped cutaway portions 25 are provided in the dome 26 to permit of the exit of the gases to the exterior of the whistle. This dome por-

tion is hollow as at 27. The face of the cutaway portions 25 are bevelled as at 28 and the inner edges thereof are substantially in line with the outer edge of the cap member 21.

While we have shown and described certain features as constituting our invention, it will be understood that parts have been shown for purposes of illustration only, and 10 that we do not desire to be limited to such details, as obvious modifications will occur to a person skilled in the art.

Having thus fully described our invention, what we claim as new and desire to 15 secure by Letters Patent is:—

1. A two-part automotive exhaust whistle comprising a lower part having a hollow attaching nipple opening into an expanded chamber, said chamber having on its exterior 20 a threaded flange, a disk above said chamber having cut away portions and supported on legs integral with said lower portion and disk, a dome screw-threaded for attachment to said flange and having 25 legs which when attached to the lower portion and adjusted for use, stand opposite the legs on the lower portion of the whistle, said disk filling said dome portion except

for the cut away portions at the periphery of the disk, said dome having cut away 30 portions above the cut away portions in the disk.

2. In an automotive exhaust whistle, a conduit having a collar at one end, an annular flange formed integral with and 35 aligned with the top of said collar, a plurality of spaced legs formed integral with said flange and aligned with the outward end of said collar, a disk formed integral with and aligned with the outer ends of said 40 legs, said disk also having cutaway portions to co-operate with the spaces between said legs, a dome having a cut away portion, said cut away portion extending to the top of said disk and aligned with the outer edge 45 of said disk, said dome projecting outwardly from the end of the cutaway portion and extending to the outer edge of said flange, means for attaching said projection portion to said flange, and said dome having ports 50 in its cutaway portion.

In testimony whereof, we affix our signatures.

ROBERT C. ANDERSON.
FREDERICK F. RIKE.
